UNITED STATES PATENT OFFICE.

RICHARD J. SCHOESSOW, OF EMBDEN, NORTH DAKOTA.

TIMER COVER.

Application filed April 25, 1925. Serial No. 25,877.

To all whom it may concern:

Be it known that I, RICHARD J. SCHOESSOW, a citizen of the United States, residing at Emden, in the county of Cass and State 5 of North Dakota, have invented certain new and useful Improvements in Timer Covers, of which the following is a specification, reference being had to the accompanying drawings.

- 10 This invention relates to timer covers and more particularly to a timer cover for that type of engine wherein the timer is located at the forward end of the base of the engine immediately in the rear of the radiator and 15 at a point low down upon the engine where it is subject to the action of water and oil. An important object of the invention is 20 to provide a device of this character which not only effectually prevents water and oil from reaching the timer but which likewise serves to support the adjacent portions of the timer wires so that they do not come into contact with collected dirt and grease which tends to deteriorate the same.
- 25 A still further object of the invention is to provide a device of this character which is very readily applied to the engine or removed therefrom and which may be produced at a very low cost.

- 30 These and other objects I attain by the construction shown in the accompanying drawings, wherein for the purpose of illustration is shown a preferred embodiment of my invention and wherein:—

35 Figure 1 is a front elevation showing a timer cover constructed in accordance with my invention applied to the timer of a vehicle;

40 Figure 2 is a horizontal sectional view therethrough;

45 Figure 3 is a rear perspective of the timer cover removed; and

Figure 4 is a detailed sectional view taken through the end of the timer cover showing the manner of applying the closure plate 27.

50 Referring now more particularly to the drawings, the timer cover comprises an outer plate 10 having a main portion 11 substantially circular in form which is adapted to be positioned over the timer and an extension 12, one face of which is tangential to the circular portion 11. The circular portion 11 may, if so desired, be shaped to conform substantially to the shaping of the timer T with which it is to be employed.

55 About the edges of the circular portion 11

and its extension 12, a flange is provided, indicated at 13. That portion of the flange 13 corresponding to the junction of the upper edge of the section 12 with the circular portion 11 is notched, as at 14, for a purpose presently to appear.

At the opposite side of the circular portion 11 from the extension 12 and at what is the upper portion of the flange 13 when the cover is in applied position, a second notch 15 is formed in this flange. At this notch, the flange is provided with an extension 16 overlying the notch and from this extension, a vertical wall 18 extends downwardly at the front of the notch. The extension 16 and wall 18 combine to form a hood protecting against the entry of water at the notch 15. The upper surface of the flange 13 between the extremity of the extension 16 and the adjacent edge of the notch 14 has secured thereto a felt strip 19 which may be held in position in any desired manner. In the present illustration, this felt strip is held in position by an applied metallic strip 20 secured in position by split rivets 21. The edge of this felt strip, indicated at 22, projects beyond the edge of the flange 13 for a purpose presently to appear.

In the type of engine to which this device is to be employed, the timer key is located against the front face of the timing gear cover C. This timing gear cover is secured to the engine base by bolts, certain of which are arranged at the lower end of the cover and indicated at B are in approximate alignment. In the construction of the disk 11, this is made of such size that the bolts are barely cleared and the straight face of the flange 13 between the disk and extension 95 will come immediately above these bolts when the cover is in applied position. The timer is shifted by a rod R to control the timing of the engine. Also in this type of engine, the timer cover embodies what is known as a breather pipe P to which is attached an arm A, the end of which extends over the timer for engagement in a depression formed centrally thereof. Until this arm is in position, there is nothing whatever to hold the timer in its position against the face of the cover and I have accordingly formed in the disk 11 an opening 23 through which a finger may be inserted for engagement with the timer to hold it in position 100 while the cover is being properly positioned. A swinging cover 24 is provided for this

opening. Immediately above the depression D of the timer T, the cover is formed with an opening 25 through which a pin carried by the end of the arm A may be inserted for engagement in the depression D. In accordance with my invention, this arm is further provided with a set-screw 26 for engagement against the disk 11 to hold the same firmly in position against the face of the timer cover. The notch 14 permits the flange to conform to the shaping of the timer cover at the breather pipe while the notch 15 accommodates the rod R.

It will be obvious that those portions of the timer cover extending beyond the edges of the timer gear cover and formed by the extension 12 will have an open rear face. In the application of the cover, the lead wires from the timer, indicated at L, are directed through this extension and beyond the edge of the timer gear cover C. A closure plate 27 is then applied to the rear face of the extension. This closure plate has one edge 28 thereof shaped to conform to the shaping of the adjacent edge of the timer gear cover C and is of such length that it provides between the end of the extension and its end a space 29 through which the lead wires may be directed. This closure plate is in the form of a flat sheet having on one of its edges hooks 30 for engagement in openings 31 formed in the lower portion of the flange 13 and upon its opposite side edge resilient hooked arms 32 for engagement in similar openings 33 formed in the upper portion of the flange 13. These arms may be swung into position and when engaged will maintain the closure plate at the proper point. The gasket or felt strip 19 will firmly engage against the timing gear cover and provide a seal between the upper portion of the flange of the plate and the timing gear cover preventing entry of moisture which may run down the face of the timing gear cover.

I claim:

1. A timer cover for the timers of engines having a timing gear cover against which the timer abuts, said timer cover comprising a plate adapted to confront the timer and having a reduced extension projecting therefrom at one side and of a length to project beyond the edge of the timing gear cover, said plate and its extension having flanges at their side edges, those portions of the flanges adapted to oppose the timing gear cover being shaped to conform thereto, the flange of the plate having a hooded notch for the passage of an operating rod for the

timer, said extension and its flanges combining with the timing gear cover to provide a conduit for the lead wires of the timer, the flanges of the extension at that portion thereof projecting beyond the side of the timing gear cover being connected with the exception of the outer ends thereof by a removable cover plate to thereby provide an extension of such conduit.

2. A timer cover for the timers of engines having a timing gear cover against which the timer abuts, said timer cover comprising a plate adapted to confront the timer and having a reduced extension projecting therefrom at one side and of a length to project beyond the edge of the timing gear cover, said plate and its extension having flanges at their side edges, those portions of the flanges adapted to oppose the timing gear cover being shaped to conform thereto, the flange of the plate having a hooded notch for the passage of an operating rod for the timer, said extension and its flanges combining with the timing gear cover to provide a conduit for the lead wires of the timer, the hood of said notch and the upper portion of the flange of the plate being provided with a compressible gasket, the edge of which projects beyond the edge of the flange for engagement with the timing gear cover to provide a seal thereagainst.

3. A timer cover for the timers of engines having a timing gear cover against which the timer abuts, said timer cover comprising a plate adapted to confront the timer and having a reduced extension projecting therefrom at one side and of a length to project beyond the edge of the timing gear cover, said plate and its extension having flanges at their side edges, those portions of the flanges adapted to oppose the timing gear cover being shaped to conform thereto, the flange of the plate having a hooded notch for the passage of an operating rod for said timer, said extension and its flanges combining with the timing gear cover to provide a conduit for the lead wires of the timer, the plate having an opening formed therethrough, an arm secured to the timing gear cover and provided at its end with a pin adapted to extend through said opening to engage the timer and maintain the same in position and a securing element directed through said arm for engagement with said plate.

In testimony whereof I hereunto affix my signature.

RICHARD J. SCHOESSOW.
